UNITED STATES PATENT OFFICE.

WILHELM HARTMANN, OF OFFENBACH-ON-THE-MAIN, GERMANY.

ASH-EJECTING MECHANISM.

1,209,703.

Specification of Letters Patent. Patented Dec. 26, 1916.

Application filed November 16, 1914. Serial No. 872,500.

To all whom it may concern:

Be it known that I, WILHELM HARTMANN, a subject of the German Emperor, residing at Offenbach-on-the-Main, Germany, have 5 invented certain new and useful Improvements in Ash-Ejecting Mechanism, of which the following is a specification.

The removal of hot ashes, clinkers and the like waste material in large furnace installations, for example marine boiler furnaces, is, as is well known, extremely inconvenient by reason of the large quantities of dust and deleterious gases evolved, and also by reason of the heat of the ashes. The hot material 15 also always had to be separately slaked previous to removal.

Now the invention has for its object to remove these disadvantages, and it relates to an arrangement by which such waste material as hot ashes, clinkers and the like is directly carried off by means of air under suction, not only without raising dust, but also with water cooling or slaking.

The invention is characterized by the feature that the conveyer pipe of the ash ejecting mechanism, which operates the removal or conveyance of the material, passes the latter directly into a second pipe, in which water or the like is permanently maintained 25 at a given level by suction action, which water is introduced from the outside, either from a separate tank, or, in the case of ships, directly from overboard, in such a way that the hot material is passed directly into the 30 water and is discharged through it while the suction air passes into the pump entirely freed from dust and purified.

A form of construction of the invention is illustrated in the accompanying drawing. 40 This figure is a diagrammatic view of a container such as a ship's hull S on the deck D of which, or in any other suitable place, the suction chamber a is erected. This suction chamber is kept under permanent 45 vacuum through a pipe d in known manner by means of an air pump erected in any suitable place on the ship, and which is not shown in the drawing. A discharge pipe e leads down from the chamber a and its lower 50 end opens through the ship's hull into the water outside, while its upper end connects with the suction chamber a by means of a nozzle e'. The upper part of the pipe e is widened and so shaped as to form a 55 curved chamber e². A movable pipe k leads upwardly from the interior of the ship

through the deck and extends through the suction chamber a, in which it is curved first downwardly, then again upwardly, and projects into the nozzle e' which, as shown, is of 60 larger diameter than that of the conveyer pipe k. As by the vacuum in the chamber a water is drawn up from overboard through the pipe e and maintained at such a height that it surrounds the mouth of the conveyer 65 pipe k. The entire material is raised through the conveyer pipe k and is ejected from said pipe into the chamber e² through the slaking water. The slaked material ejected from the pipe k then falls into the 70 water of the pipe e and sinks therethrough into the sea, while the air passing through the water surrounding the mouth of the pipe k is drawn into the suction chamber a and thus reaches in a purified state the pump 75 through the pipe d. The suction pipe k terminates at its lower end directly in front of the boiler furnace, and is made movable so that ashes, slag and the like can be drawn 80 directly from the front of the furnaces and conveyed overboard without any annoyance of dust, gas or heat.

The operation is as follows: The chamber a being held constantly at a vacuum, the ashes, clinkers, etc. will be drawn through 85 the pipe k and owing to the great velocity with which the air passes through the latter, will be thrust through the nozzle e' into the chamber e², as indicated by the dotted arrow. Simultaneously in accordance with 90 the vacuum created in the chamber a water will rise into the pipe e to such a level as to surround the mouth of the pipe k. The material conveyed through the pipe k will be ejected into the chamber e² through the 95 water surrounding the mouth of the pipe k, whereby it will be cooled, while the air traveling together with the material will in passing through the water become purified and pass into the chamber a and thence to 100 the pump through the pipe d.

What I claim and desire to secure by Letters Patent is:

1. In an ash ejecting mechanism, the combination with a container and a water supply, of a suction chamber, a conveyer pipe leading from the container through said chamber, a discharge pipe leading from the water supply and formed with a wider part 105 communicating with the said chamber and into which said first pipe projects, both said pipes being exposed to the suction action 110

created in said suction chamber and the discharge pipe being adapted under the suction action to draw water from the water supply to such a level as to surround the mouth of the said conveyer pipe, so that the material conveyed from the container by suction is thrust through the water surrounding the mouth of the conveyer pipe into the discharge pipe while the air traveling with the material is purified.

2. In an ash ejecting mechanism, the combination with a floating vessel, of a suction chamber, a conveyer pipe leading from the interior of the vessel through said chamber, a discharge pipe, one end of which communicates with the water outside of the vessel and the other end of which has a wider portion which communicates with the suction

at the Commissioner of Patents, Washington, D. C.

chamber and into which the conveyer pipe terminates, both said pipes being exposed to the suction action in said suction chamber, and the discharge pipe being adapted under the suction action to draw water from the outside to a level at which it surrounds the mouth of the conveyer pipe, so that the material conveyed through the conveyer pipe will be ejected into the said discharge pipe through the water surrounding the mouth of the conveyer pipe, while the air traveling with it is purified.

In testimony whereof I affix my signature in presence of two witnesses.

WILHELM HARTMANN.
